A. BROADMEYER

UNDERLIFT FOR RULING PENS

Filed July 2, 1925

FIG. 1.

FIG. 2.

Albert Broadmeyer
INVENTOR

BY

R. J. Foster
ATTORNEY

UNITED STATES PATENT OFFICE.

ALBERT BROADMEYER, OF HARRISBURG, PENNSYLVANIA, ASSIGNOR TO W. O. HICKOK MFG. COMPANY, OF HARRISBURG, PENNSYLVANIA, A CORPORATION OF PENNSYLVANIA.

UNDERLIFT FOR RULING PENS.

Application filed July 2, 1925. Serial No. 41,159.

The present invention relates to means for engaging the ruling pens of a ruling machine to raise the same from the paper, said means being generally known as "underlifts."

The object is to provide a simple device for the purpose that can be readily positioned with respect to a pen and is easily adjustable to effect the desired lifting action.

10 In the accompanying drawings:—

Figure 1 is a detail perspective view of a portion of a ruling machine illustrating two of the underlifting devices in associated relation to the pens.

15 Figure 2 is a sectional view through the rock shaft for the underlift devices, and a side elevation of one of said devices detached from the shaft.

In the structure as disclosed, a portion of 20 a pen beam is indicated in outline at 3, and carries a plurality of pens, shown at 4. Operating beneath the pen beam and pens is the usual sheet conveyor in the form of a belt or cloth 5. These parts are well-known, 25 and it is believed unnecessary to go into further detail regarding them. Located below the pens 4 is a rock shaft 6 that is angular in cross section, and may have one of its faces roughened or knurled, as illustrated at

30 7. On this shaft are located the underlift devices. These devices each consists preferably of a single piece of sheet metal having some resilience, as for example, spring brass. The strip has one end portion formed into 35 an angular loop or open collar 8. The open side is preferably of less width than the shaft 6; the other end of the strip extends outwardly from the loop and constitutes a pen-engaging arm or finger 9.

40 In using the underlift, the loop is sprung upon the shaft 6 and frictionally engages the same, the arm outstanding beneath the pen, as illustrated in Figure 1. This arm may be readily bent to position, so that when 45 the shaft is turned in one direction, it will engage the free end of the pen and lift it from the paper, and when the shaft is turned

in the opposite direction it will disengage the pen and allow it to rest upon the paper. Obviously these underlift devices can be 50 cheaply manufactured and may be readily placed in any desired position on the shaft, being slidable along the same to any point desired.

From the foregoing, it is thought that the 55 construction, operation and many advantages of the herein described invention will be apparent to those skilled in the art, without further description, and it will be understood that various changes in the size, 60 shape, proportion and minor details of construction may be resorted to without departing from the spirit or sacrificing any of the advantages of the invention.

What I claim, is:

1. An underlift for ruling pens comprising a rock shaft with flat faces, and a pen-engaging arm having a collar portion that embraces the shaft and provided with substantially flat faces that bear against the flat 70 faces of the rock shaft.

2. An underlift for ruling pens comprising a rock shaft that is angular in cross section, and a pen-engaging arm having a collar portion that is angular in form and embraces the shaft.

3. An underlift for ruling pens comprising a rock shaft having a substantially flat roughened face, and a pen-engaging arm having a collar portion that embraces the 80 shaft and is slidably thereon, said collar portion bearing against and being held against accidental displacement by the roughened portion.

4. An underlift for ruling pens comprising a rock shaft that is angular in cross section and has one of its flat faces roughened, and a pen-engaging arm having an angular collar portion that embraces the shaft and has a substantially flat side bearing against 90 the flat roughened face of the rock shaft.

In testimony whereof, I affix my signature.

ALBERT BROADMEYER.
